UNITED STATES PATENT OFFICE.

GIANNI BETTINI, OF NEW YORK, N. Y.

GOLF-PRACTICE DEVICE.

Application filed February 24, 1923. Serial No. 620,916.

This invention is a novel golf practice device, and the main object is to provide a simple, inexpensive and durable device by which the various strokes employed in the game of golf may be practiced in a restricted space. Another object is to employ the principle of a captive ball in such a way as to give freedom in the making of the stroke with the various clubs used in golf, for the purpose of training on various shots. Another object is to afford a measure of the speed of the struck ball and the probable distance of travel. A further object is to give a much better measure of the distance of a drive or other shot by indicating the elevation or upward slant of the driven ball, this being very important not only in driving for distance but also in the matter of surmounting hazards, etc. The combined measures of speed and elevation afford a very good estimate of the effectiveness of the stroke as regards distance attained. Other objects and advantages of the present invention will be pointed out in the following description of one specific illustration or embodiment or will be apparent to those skilled in the art. To the attainment of such objects and advantages the present invention consists in the novel device, mechanism, combinations, arrangements and details herein described or illustrated.

In the accompanying drawings Fig. 1 is a vertical section of a golf practice device embodying the principles of the present invention. The cable or tether is shown broken away to indicate a greater length, and in repose the ball will rest not as indicated in full lines, but on the floor at a point several feet from the base. During its circular travel the ball will whirl around at an elevated point, not as indicated in dotted lines, but with the tether extending out and up at an angle, the device itself taking a position as indicated in dotted lines.

Fig. 2 is a top plan view of the device shown in Fig. 1.

Fig. 3 is a side elevation of the entire device showing how the tether and ball will stand when in readiness to make a stroke.

The base 3 is shown as having an upright hollow post 4 on the top of which rotates a table or disk 5. This rotary table carries the mechanism to which the tether is attached and the table rotates as the traveling ball whirls around the base. This table might take various forms but is shown as a

circular disk mounted at the upper end of a depending shaft 6, which extends down through the hollow of the post 4 and has a head or enlargement 7 attached to its lower end. This enlargement serves as a means for the attachment of a flexible shaft 8 serving as a transmitting means to convey the rotary motion to the index or device for measuring the speed or travel of the ball. 60 The opposite end of the shaft 8 may pass into a fixed bearing 9 where it is arranged to turn a worm 10 acting upon a worm wheel 11 mounted on a short shaft or stud 12, which extends through from the interior of 70 the base to a visible point at the exterior. The stud 12 is extended in the form of a threaded rod 13 and on this rod is loosely mounted the index pointer or finger 14, with a spring washer 15 between the pointer and 75 the stud. A thumb nut or adjuster 16 is shown surrounding the threaded rod 13 and attached to the finger 14, and a holding screw 17 maintains the parts in position. By this arrangement the rotation of the table 5 due to the whirling travel of the ball is communicated to the pointer 14 and this travels around a conveniently graduated scale 18 in which the indications may roughly be arranged to indicate the number of 80 yards of travel. In order that the illustrated tether, of a length for indoor use, may be replaced by a longer one, for outdoor use, the scale 18 may have two sets of indications, corresponding to the ratio of the 85 circumferences of travel of the indoor and outdoor tethers respectively. As before stated, the actual travel of the driven ball will depend not only on its speed, which will largely control the reading on scale 18, 90 but on its elevation, to be measured, as will later be described. Therefore, the player after observing the distance indicated on scale 18, about 288 yards in Fig. 2, will make due allowance for a greater or less distance 95 in accordance with the elevation of the drive as indicated on the other scale to be described. By experience or test a table or formula can readily be arranged coordinating these two factors; but aside from that 100 the knowledge of these two factors is of importance and interest to a practicing player.

Describing now the means by which the captive ball is connected, the rotary table 5 is shown as provided with a pair of up-standing plates 19 forming a two-sided bracket. A pivot or pin 20 extends through

these plates and constitutes a fulcrum for a swinging arm 21 to which the tether and ball are attached. It will be noticed that this arm slants downwardly from the pivot 20 and its far end is curved up slightly and its extremity curled into a short helix 22 forming a very convenient hook to which the tether can be attached and from which it can be readily detached for interchange or other purposes, without any danger of accidental detachment. The arm 21 is provided with a spring extension 23, slightly upcurved, and provided at its extremity with an eye or ring 24. This described arrangement is as shown 15 in Figs. 1 and 2. Fig. 3 shows an alternative arrangement, the tether 25 carried through the eye 24 and thence directly to the hook 36 which is near the vertical axis of a rotation of the device. This hook 36 is also indicated in Fig. 1, but is not in use. This arrangement gives a better action. When the ball is struck, the lift of the ball first carries it to a height such as indicated in dotted lines in Fig. 3, this action adjusting 20 the index 31, 32 to show the elevation. Thereupon the continued whirling of the ball will be at a lower level, for example, substantially at the point 27^a in Fig. 3.

The tether 25, rather than being a cord 30 of fibrous material is preferably a cable or flexible shaft constructed of metal and possibly hollow. It may be a substantial duplicate of the flexible shaft 8, before mentioned, and its characteristics are that while it will 35 bend to a certain degree its tendency is to straighten and it is not extensible or twistable. The tether is formed with a ring which is engaged with the curled hook 22 and the tether then passes through the eye 24 and is of several feet in length, perhaps 40 four feet more or less. At its end it is provided with a headed pin 26 on which the golf ball 27 is loosely fitted, the ball being perforated for this purpose, and a nut 28 45 serving to hold the ball upon the pin. By this rotary mounting of the ball it is capable of spinning during flight without any twisting effect upon the tether.

The rotary table 5 is shown also as being 50 provided at its opposite side with a counter-weight 29, which may be fixed to the bracket 19 and serves the double purpose of partly counteracting the centrifugal force of the ball, the weight being heavier but with a 55 shorter radius, and increasing the momentum so as to give a more efficient action, minimizing the retarding effect of the friction in the device.

While the index for the speed or travel of 60 the ball is preferably mounted on the base, on the contrary the contrivance or index for measuring the elevation of the ball's trajectory is preferably mounted at the top of the device, above the rotary table 5. It will 65 be understood that when the driven ball

rises in the air as it starts its circular flight it will lift the tether end through it the arm 21, these parts assuming an upward slant which constitutes a measure of the elevation of the stroke. The fact that the arm 70 21 is pivoted at 20 permits this upswing movement. This possesses another important function, namely that it minimizes any tendency of the traveling ball to vibrate upwardly and downwardly as it travels 75 around. The arm will swing up to this position in accordance with the elevation of the stroke. A shot with a loftier will give a greater elevation than a driver, and a mashie a greater elevation than a loftier if 80 the club is properly handled, and this invention gives a measure of this fact. In Fig. 1 in dotted lines the arm and tether are indicated as elevated to a point which is measured at 25 on the scale, to be described. 85 It will be understood that the first part of the tether is shown substantially in proper position, but beyond the eye 24 the tether should continue in a straight upwardly inclined direction to indicate the ball in flight. 90 As will be explained, when the ball has come to rest the elevating arm is retained in its elevated position and the dotted lines in Fig. 1 may be considered as indicating this position, the ball however resting idly on the 95 ground since the tether is considerably longer than in the drawing, as indicated by the break in its length.

For measuring the elevation there is attached to the bracket 19 an upstanding plate or quadrant 30 provided with a scale or graduations 31. The arm 21 is provided with a finger or indicator 32, which stands at zero in full lines at Fig. 1, but in the elevated dotted position stands at 25. Whether or not the degrees marked on this scale 100 represent the actual elevation of the stroke, they give a measure of the elevation and a means of comparison between different strokes in order to obtain perfection. Obviously the scale could be regraduated in 105 any desired manner.

When the ball is struck and starts its whirling travel, tautening the tether 25, the arm, the tether and the ball all stand out 110 from the pivot 20 in a straight line. This elevated position is what is measured by this invention so as to give a measure of the elevation of the stroke. The measure would be lost if the arm were allowed to swing 115 downwardly, but in this invention an arrangement is provided which retains the indication of the elevation, so that when the apparatus has come to rest the player can 120 examine the scale 31 to gain an indication 125 of the elevation of his stroke. For this purpose preferably the arm 21 itself is held up to its elevated position. It is shown as provided with a ratchet wheel or segment 33 located at the outer side of one of the 130

bracket plates 19 and secured upon the pivot shaft 20. In connection with this ratchet is a spring lifted pawl 34. The dotted lines indicate how the ratchet has traveled along 5 the pawl and is held with the arm 21 in elevated position. The ratchet may be formed with finer teeth than as shown to give a more accurate measure. The pawl is provided with an extension or handle 35 10 which may be depressed to allow the arm to drop and restore the parts to zero.

The operation has been sufficiently described, but may be explained further as follows. The ball will be laid upon the 15 floor or a suitable support several feet away from the base 3. The player will stand facing the base 3 and in line with the tether 25 so that his stroke will be tangential to the circular path the ball is to take. The ball is 20 driven or lifted, as desired, and it rises to varying heights above the floor and travels rapidly around the base of the machine, finally slowing down and coming to rest. The player then reads the two indexes to acquire 25 a measure of the distance of travel, and the elevation. He then depresses the finger 35 to restore the arm to zero and turns the thumb nut 16, by which the finger 14 may be brought back to zero, due to the friction 30 between the finger and the shaft 12.

Many matters of combination, design and arrangement may be variously modified without departing from the principles involved and it is not intended to limit the 35 invention to such matters except so far as set forth in the appended claims.

What is claimed is:

1. In a golf practice device, a base, an upright thereon, a rotatable member on said upright, an outstanding arm connected to said rotatable member and capable of swinging upwardly, a flexible ball tether connected with said arm, an indicator operated according to the rotation of the rotatable 45 member to give a measure of forward travel, and a separate indicator operated by the upswing of the arm to give a measure of the ball's elevation.

2. In a golf practice device, a base, an upright shaft rotatably mounted above said

base, an upswinging arm mounted at the upper end of said shaft, a tether and ball secured to said arm, an indicator on the base actuated from said shaft to measure the ball's forward travel, and an indicator at 55 said arm to measure its upswing and the ball's elevation.

3. In combination, a base, a post thereon, a rotatable table on said post, an arm, tether and ball connected to said table, a dial indicator on the base, and a rotatable connection between said table and indicator. 60

4. Combination as in claim 3 and wherein in the connection between the table and base-dial comprises, an upright shaft below the 65 table, a flexible shaft turned by said upright shaft, and a speed-reduction gear, such as worm and wheel between the flexible shaft and indicator.

5. Combination as in claim 3 and wherein in is a friction or slip connection, enabling the indicator to be reset to zero. 70

6. In a golf practice device, a base, an upright thereon, a rotatable member on said upright, an upswinging arm connected to 75 said rotatable member, and a flexible ball tether connected with said arm; said upswinging arm normally slanting downward toward a distant point on the floor and having releasable means for detaining it in elevated position.

7. In a golf practice device, a base, a rotatable member supporting said base, an outstanding arm connected to said member and capable of swinging upwardly, said 85 arm having a spring extension with an eye thereon, and a flexible ball tether passing through said eye and secured to said arm nearer to the center of rotation.

8. In a golf practice device, a base with 90 a post thereon, a revolving member on the post, an outstanding arm carried by the member, and a ball tether connected to said arm consisting of a metallic flexible shaft or cable, resistant to substantial flexing, non-stretchable and non-twistable. 95

In testimony whereof, I have affixed my signature hereto.

GIANNI BETTINI.
